UNITED STATES PATENT OFFICE.

WILLIAM B. JARVIS, OF GRAND RAPIDS, MICHIGAN.

RADIATOR CAP AND THE LIKE.

Application filed February 6, 1926. Serial No. 86,452.

The main objects of this invention are:

First, to provide an improved radiator cap which is effectively sealed against the escape of air or steam around the cap or between the cap and neck upon which it is engaged.

Second, to provide a radiator cap having means for retaining it adjustably and removably upon the radiator neck so that the ornamental or other projecting features on the cap may be properly alined or positioned relative to the radiator.

Third, to provide a cap having these features which is comparatively simple and economical in structure, has an attractive finished appearance, both internally and externally, and one in which the spring parts thereof are effectively protected.

Objects relating to details and economies of my invention will definitely appear from the detailed description to follow. The invention is clearly defined and pointed out in the claims.

A structure which is a preferred embodiment of my invention is illustrated in the accompanying drawing, forming a part of this application, in which:

Fig. 1 is a vertical central section of a radiator cap embodying the features of my invention, a fragment only of the radiator being shown.

Fig. 2 is a perspective view of the spring member of the embodiment shown in Fig. 1.

Fig. 3 is an enlarged detail on a line corresponding to line 3-3 of Fig. 2.

Fig. 4 is a perspective view of the internal closure member of the cap.

Fig. 5 is a vertical central section of a modified form or embodiment of my invention.

Fig. 6 is an inverted view of the cap with certain parts omitted.

Fig. 7 is a plan view of the thrust member of the embodiment of Figs. 5 and 6.

In the drawing similar reference characters refer to similar parts throughout the several views.

Referring to the drawing, 1 represents the threaded neck of an automobile radiator. In the embodiment shown in Fig. 1, the cap 2 is internally chambered and is provided with projecting ornamental wings 3, one only of which is illustrated.

The cap has an internal annular shoulder 4 constituting a support for the thrust member 5 which is formed of spring brass or

other suitable material and has a plurality of spring tongues 6 struck out therefrom. Between the threaded portion 7 of the cap and the shoulder is an unthreaded portion 8. The gasket 9 is disposed in this unthreaded portion to coat with the end of the neck 1.

I provide a part 10 which for convenience I designate a closure member and this in the embodiments illustrated is cupped or spherically curved and provided with a peripheral flange 11, the flange being arranged between the gasket and the spring thrust member. This closure member performs several functions, it coating with the gasket to provide a seal so that water or steam cannot pass around the gasket and escape through the threads. It also provides a wear plate for the gasket or between the gasket and the spring thrust member so that the gasket is not injured and distorted by the threading of the cap into place.

This closure member also provides a uniform pressure or thrust member between the gasket and the spring means, and is free to rotate with the gasket, or the cap may be rotated independently of this closure member, thereby relieving the gasket of wear and distortion. Further, it provides a neat and attractive finish for the inside of the cap.

My improvements are capable of wide adaptation or embodiment and in Figs. 5, 6 and 7 I show my present improvements embodied or adapted to a structure of the character shown in my application for Letters Patent, Serial No. 25,272, filed April 23, 1925. In this embodiment the cap is provided with a central depending stud 13 and an annular abutment shoulder 14 having spaced recesses 15 therein receiving the inwardly projecting fingers 16 on the annular spring member 17. This spring member is retained with its fingers in engagement with these recesses and supported by the thrust shoulder by means of the clamping disk 18 mounted on the stud and secured thereon by means of the nut 19. The closure member is arranged between the thrust member and the gasket the same as shown in Fig. 1.

With this arrangement of parts a substantially perfect seal is provided, that is, the water and steam cannot escape around the gasket as the closure is in sealing contact therewith and it cannot escape under the gasket owing to its being yieldingly held against the end of the neck. It is not necessary with this arrangement that the gasket

shall be a perfect fit and, further, uniform thrust is provided on the gasket and it is not worn or distorted in turning the cap upon or from the neck. The cap may be adjusted to desired position to present projecting parts, or a dial or the like in proper position.

I have not attempted to illustrate and describe certain embodiments and adaptations 10 of my improvements to other forms or types of caps as it is believed that the disclosure made will enable those skilled in the art to embody or adapt my improvements as may be desired.

15 Having thus described my invention what I claim as new and desire to secure by Letters Patent is:

1. The combination with a threaded neck, of a cap threaded to engage said neck, an annular spring member provided with a plurality of spring tongues disposed within said cap in opposed relation to the end of the neck, a gasket engaging the end of the threaded neck, and a cupped closure member 25 having a peripheral flange disposed between said gasket and said spring member.

2. The combination with a threaded neck, of a cap threaded to engage said neck, an

annular thrust member provided with a plurality of spring tongues disposed within said cap, and a closure member disposed with its periphery between the end of the neck and said spring thrust member.

3. The combination with the threaded neck, of a chambered internally threaded cap having a downwardly facing annular shoulder, an annular thrust member provided with a plurality of downwardly projecting spring tongues disposed against said shoulder, a closure member disposed within said cap to engage said spring tongues, and a gasket disposed below said closure member to engage the end of the radiator neck.

4. The combination with a threaded neck, of a cap threaded to engage said neck, an annular thrust member provided with a plurality of spring tongues disposed within said cap, a gasket engaging the end of the neck, and a closure member having its periphery disposed between the gasket and said spring thrust member, the cap and closure member being independently rotatable.

In witness whereof I have hereunto set my hand.

WILLIAM B. JARVIS.
